CLAIM

The ornamental design for a printer, as shown and described.

DESCRIPTION

FIG. 1 is a perspective view of a printer.

FIG. 2 is a top view of the printer of FIG. 1.

FIG. 3 is a right side view of the printer of FIG. 1.

FIG. 4 is a left side view of the printer of FIG. 1.

FIG. 5 is a front view of the printer of FIG. 1.

FIG. 6 is a back view of the printer of FIG. 1.

FIG. 7 is a perspective view of the printer of FIG. 1 in which the output tray has been extended.

FIG. 8 is a top view of the printer of FIG. 1 in which the output tray has been extended.

FIG. 9 is a right side view of the printer of FIG. 1 in which the output tray has been extended.

FIG. 10 is a left side view of the printer of FIG. 1 in which the output tray has been extended.

FIG. 11 is a front view of the printer of FIG. 1 in which the output tray has been extended; and,

FIG. 12 is a back view of the printer of FIG. 1 in which the output tray has been extended.

Any portions shown in broken lines in the figure are for illustrative purposes only and form no part of the claimed design.
